UNITED STATES PATENT OFFICE.

AUGUST G. LIEBMANN, OF BUTTE, MONTANA, ASSIGNOR TO VIGNOLE'S RAIL CHAIR COMPANY, OF NEW YORK, N. Y., A CORPORATION OF DELAWARE.

RAIL-CHAIR.

1,126,498.

Specification of Letters Patent.

Patented Jan. 26, 1915.

Application filed April 28, 1913. Serial No. 764,149.

To all whom it may concern:

Be it known that I, AUGUST G. LIEBMANN, citizen of the United States, residing at Butte, in the county of Silverbow and 5 State of Montana, have invented certain new and useful Improvements in Rail-Chairs, of which the following is a specification.

This invention relates to railway track app- 10 pliance and particularly to rail chairs, and means for holding the rail in place therein and adjusting the rail.

When rails are held to the ties merely by spikes engaging the base flanges of the rail, 15 the thrust incident to the passage of a train tends constantly to loosen or withdraw the spikes. The vertical thrust of the rolling stock tends to force the rail into the tie crushing and breaking the fibers of the same. 20 The lateral thrust tends to shear the spikes or loosen them, and the tipping thrust tends to tip the rails upon one side edge of the base flange and raise the other side edge, thus withdrawing the spikes. As a conse- 25 quence, there is constant necessity of re-driving and renewing spikes and ties. Furthermore, where spikes are used any de- 30 pression or elevation of one portion of a rail or section of a track under, for instance, the action of frost or thaw, tends to cause either a withdrawal of the spikes, or the base flange of the rail will shear if the spikes can not be withdrawn.

The primary object of the present invention 35 is the provision of a very simple form of rail chair in which the rail is to be seated which may be readily formed by rolling and pressing, and in which to this end the body of the chair is made from a deformed I- 40 beam section.

The further object is to so form a chair 45 that the rail will be fully supported against vertical or lateral thrust or any tipping action. The chair with oppositely disposed abutments between which the rail is seated 50 permits the use of rail clamping wedges between the abutments and the brace or lining plates of the rail, these rail clamping wedges permitting the rail to be laterally adjusted between said abutments so that the rails of the track may be brought to gage and readily kept in gage.

The still further object is to so form a chair that the rail may be readily adjusted

vertically by means of shims and then held 55 rigidly in its adjusted position.

Another object is to so form the chair that the clamping wedges whereby the rail is held shall be prevented from any vertical displacement. 60

Another object is to provide a type of chair and rail clamping means particularly adapted for use on southern lines with well drained sub-grade and rock ballast, and for either freight or passenger traffic. 65

Other objects will appear in the course of the following description.

The invention is illustrated in the accompanying drawings wherein:

Figure 1 is a perspective of a tie and rail 70 and the improved rail chair applied thereto; Fig. 2 is a plan view partly in section of the construction shown in Fig. 1; Fig. 3 is a vertical sectional view on the line 3—3 of Fig. 2; Fig. 4 is a transverse section of the 75 structural member from which the chair is made showing in dotted lines the way that the member is pressed in order to form the complete chair.

Corresponding and like parts are referred 80 to in the following description and indicated in all the views of the accompanying drawings by the same reference characters.

Referring to these drawings, A designates a tie and B the rail. The rail B may be of 85 any type but as shown is of a standard type. The improved chair comprises a bed plate 2 having a width preferably that of the tie and resting firmly on the upper face thereof. Extending transversely across the bed 90 plate and parallel to the direction of the rail are the abutments 3 which are spaced from each other a distance slightly greater than the width of the rail base. These abutments extend vertically to a height nearly 95 equal to the under face of the head of the rail, and are then bent inwardly at right angles to form overhanging lips 4. The bed plate with its abutments 3 is preferably 100 formed from an I-beam section. The metal of the plate is first rolled in the form of an I-beam and then the flanges of the I-beam on one side are bent outwardly at right angles to the flanges on the opposite side in the manner illustrated in Fig. 4, the dotted 105 lines showing the manner in which the flanges are bent so as to form a bed plate. It will be seen that this bed plate may be

easily formed by rolling and pressing and is an important feature in the practical construction of the chair.

Disposed on each side against the web of the rail are brace or lining plates 5. Each 5 of these plates has an inner face adapted to fit the web of the rail and upper and lower flanges each having a beveled face adapted to fit the beveled face of the base and the under face of the head of the rail:

10 Disposed between the abutments 3 and the lining plates 5 are the wooden wedges 6. These wedges are longitudinally tapered upon their outer or inner faces and upon 15 their lower or upper faces and snugly fit in the space defined by the abutments, the base flange of the rail and the outer faces of the lining plates 5. Each wedge is rabbed upon its lower face as at 7 so as to fit 20 over the lower flange of the corresponding base plate.

Regulation screw spikes 8 with or without helical steel linings are used for the purpose of securing the bed plate to the tie. 25 The seating portion of the chair is preferably as wide as the width of the tie and should be of such area as will prevent the chair from cutting into the tie, thus distributing the weight of the rail and obviating 30 any crushing action. Furthermore the greater the area of the bed plate, the less effect the tipping thrust has upon the chair. This particular type of rail chair may be cheaply made but is well adapted for use 35 on lines in warm climates where the line is well drained. It will be obvious, however, that these wedges may always be kept tight by the track walker with very little trouble. It often occurs that the rail must be adjusted 40 vertically in order to keep the line of track level as where one portion of the track has been lifted by frost and it is necessary to adjust the adjacent portions of the track. This may be readily accomplished by loosening 45 the wedges 6 and then inserting a shim 9 between the base of the rail and the rail seat on the bed plate. After the shim is driven in place, the wedges 6 are again forced inward until the lining plates 5 securely clamp the rail. It is obvious that by 50 withdrawing one of the wedges and driving the opposite wedge 6 in farther that the rail may be laterally shifted with relation to the base plate and thus it is a very easy matter 55 for the track to be kept in gage at all times whereas where spikes are used, it is a very difficult matter to keep the track in gage.

It will be particularly noted from Figs. 2 and 3 that the lining plates 5 are shorter 60 than the wedges and as a consequence when the wedges are forced in the lining plates will bite into the wedges, thus preventing accidental longitudinal shifting of the wedges unless they are positively driven out.

65 It will also be noted that the abutments 3,

being parallel to the rail and to each other have a tendency to stiffen the bed plate at points on each side of the rail where the stiffening is most desired, and further that any slight buckling downwardly of the bed-plate 70 under rail pressure will cause said abutments to curve or bend slightly inward toward the rail, and thus press the wedges into the lining plates and hold said wedges in a fixed position. 75

Particular attention may be called in connection with my improved rail chair to the official report of the Block Signal and Train Control Board of the Interstate Commerce Commission, this report being dated June 29, 1912, wherein certain requirements are laid down for rail supports and wherein the board says: "A fundamental defect in design which is most apparent is the failure to realize and appreciate the overturning movement due to the wheel flange pressure against the head of the rail. It is not sufficient that the tie should support the vertical loads and resist directly horizontal thrusts and the tendency of the track to move laterally and longitudinally, but the overturning movement must be resisted. In order that the tie may properly support the stresses transmitted to it by the rail, a suitable fastening of the rails to the ties is most essential." Further the report states that "under conditions existing in a large proportion of the railroads in this country the means of adjustment of rail to tie must be such as to admit of blocking up or shimming." The 90 board further says that adequate means should be provided for shimming or for widening gage and this means should not involve lost motion and change of adjustment. It is pointed out that the improved 95 rail chair, as heretofore described, conforms to all of the requirements referred to in this report and at the same time the fastenings are not of a complicated nature and that the chairs may be made relatively cheap. 100

What I claim is:

1. A rail chair including a bed-plate having spaced upstanding abutments defining an intermediate seat adapted to receive a rail, lining plates bearing against the web 115 of the rail on opposite sides thereof and provided with upper and lower flanges, and wedging members interposed between the abutments and lining plates and bearing against the flanges of said lining plates and 120 the base of the rail, respectively.

2. A rail chair including a bed-plate having spaced upstanding abutments disposed parallel with each other and defining an intermediate seat adapted to receive a rail, 125 lining plates bearing against the web of the rail on opposite sides thereof and having upper and lower inclined flanges, and wedge members interposed between the lining plates and abutments and having their inner 130

faces bearing against the lining plates between the flanges thereof and their lower edges bearing against the base of the rail.

3. A rail chair including a bed-plate having spaced upstanding abutments, the upper ends of which are bent inwardly to form overhanging lips, said abutments being disposed parallel to each other to form an intermediate seat adapted to receive a rail, lining plates bearing against the web of the rail on opposite sides thereof and provided with upper and lower flanges, and wedging members interposed between the inner faces of the abutments and said lining plates and having their lower edges bearing against the base of the rail, the overhanging lips of the abutments serving to confine the wedges to their seats.

4. A rail chair including a bed-plate having integral upstanding abutments disposed parallel with each other and spaced inwardly from the opposite ends of the plate, the upper ends of the abutments being bent inwardly to form overhanging lips, said abutments defining an intermediate seat adapted to receive a rail, lining plates bearing against the web of the rail on opposite sides thereof and provided with upper and lower flanges, and wedging members having their inner faces bearing against the lining plates between the flanges thereof, and their outer faces bearing against the inner faces of the abutments, the lower edges of the wedges resting directly on the base of the rail.

5. A rail chair including a bed-plate having spaced upstanding abutments formed integral therewith and spaced inwardly from the opposite ends of the bed-plate, the upper face of said abutments being bent inwardly to form overhanging lips, lining plates bearing against the web of the rail on opposite sides thereof and provided with upper and lower flanges inclined to conform to and adapted to bear against the base and head of the rail respectively, and wedging members having their inner faces bearing against the lining plates between the flanges thereof, and their outer faces bearing against the abutments beneath the overhanging lips, the lower edges of said flanges bearing directly against the base of the rail.

6. The combination with a rail, of a chair consisting of a bed-plate, oppositely disposed abutments extending upwardly from the bed-plate in parallel relation to each other and spaced from each other a distance greater than the width of the base of the rail, lining plates bearing against the web of the rail on opposite sides thereof, and longitudinally tapered wedges interposed between the abutments and lining plates and bearing against the base of the rail, said wedges being greater in length than the lining plates and of softer material than said

lining plates, whereby when the wedges are forced home the lining plates will sink into the material of the wedges and bind therein from longitudinal movement relative thereto.

7. The combination with a rail, of a rail chair having a vertically disposed abutment extending at substantially right angles to the base of the rail, a lining plate bearing against the web of the rail, and a longitudinally tapered wedge interposed between the abutment and said lining plate and bearing directly against the base of the rail.

8. The combination with a rail, of a chair having means for permanent attachment to a cross tie and including a bed-plate having spaced integral upstanding abutments disposed parallel with each other and adapted to receive between them said rail, the upper longitudinal edges of the abutments being bent inwardly in the direction of the rail to form oppositely disposed overhanging lips, lining plates bearing against the web of the rail on opposite sides thereof and provided with upper and lower flanges bearing against the base and head of the rail respectively, and longitudinally tapered wedging members having their inner edges bearing against the lining plates between said flanges, and their outer edges bearing against the inner faces of the abutments, the lower edges of the wedging members bearing directly against the base of the rail.

9. The combination with a rail chair having means for permanent attachment to a sub-structure and including a bed-plate provided with upstanding abutments disposed parallel with each other and defining an intermediate seat for the reception of a rail, lining plates bearing against the web of the rail on opposite sides thereof and provided with upper and lower flanges, the upper edges of the abutments being bent inwardly to form overhanging lips disposed substantially in horizontal alinement with the upper flanges of the adjacent lining plates, and wedging members bearing against the base of the rail and entirely filling the space between the lining plates and abutments.

10. The combination with a rail, of a chair including a bed-plate provided with abutments, means for permanently attaching the bed-plate to a sub-structure, oppositely directed wood wedging members co-operating with the abutments and rail whereby the rail may be held and restored to gage, and means for permitting the adjustment of the rail vertically between the abutments independently of the permanent bed-plate securing means.

11. A rail chair including a bed-plate having upstanding abutments defining an intermediate seat adapted to receive a rail, and oppositely directed wood wedging members co-operating with the abutments whereby the rail may be held in different posi-

tions of vertical and lateral adjustment with respect to its seat.

12. The combination with a rail chair including a bed-plate having upstanding abutments defining an intermediate seat, of a rail supported on said seat and capable of being adjusted vertically with respect thereto, a removable supporting member interposed between the base of the rail and chair 10 for adjusting the rail vertically with respect

to its seat, and oppositely directed wood wedging members coöperating with the rail and abutments whereby the rail may be held in adjusted positions.

In testimony whereof I affix my signature 15 in presence of two witnesses.
